(57) **CLAIM**

The ornamental design for hand stamp, as shown and described.

DESCRIPTION

FIG. 1 is a perspective view of a hand stamp showing my new design,

FIG. 2 is a right side view thereof, the left side view being a mirror image of the right side view;

FIG. 3 is a front plan view thereof;

FIG. 4 is a rear view thereof;

FIG. 5 is a top plan view thereof;

FIG. 6 is a perspective view of a second embodiment of the design shown in FIGS. 1 through 5;

FIG. 7 is a right side view of a second embodiment thereof; the left side being a mirror image of the right side view;

FIG. 8 is a front plan view of a second embodiment thereof;

FIG. 9 is a rear plan view of a second embodiment thereof; and,

FIG. 10 is a top plan view of a second embodiment thereof.
